(57) **CLAIM**

The ornamental design for a handheld inspection light, as shown and described.

DESCRIPTION

FIG. 1 is a front elevational view of a handheld inspection light showing my new design;

FIG. 2 is a bottom plan view thereof;

FIG. 3 is a rear elevational view thereof;

FIG. 4 is a top plan view thereof;

FIG. 5 is a right side view thereof;

FIG. 6 is a left side view thereof;

FIG. 7 is a perspective view, wherein the handheld inspection light is in a folded position; and,

FIG. 8 is another perspective view wherein the handheld inspection light is in a partially unfolded position.
